UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, LONDON, ENGLAND.

AMMUNITION-HOISTING APPARATUS.

1,302,527.

Specification of Letters Patent.

Patented May 6, 1919.

Application filed May 15, 1915. Serial No. 28,492.

To all whom it may concern:

Be it known that we, Sir ARTHUR TREVOR DAWSON, knight, and JAMES HORNE, both subjects of the King of Great Britain, re-
5 siding, respectively, at Vickers House, Broadway, Westminster, in the county of London, England, and Naval Construction Works, Barrow-in-Furness, in the county of Lancaster, England, have invented certain
10 new and useful Improvements in or Relating to Ammunition-Hoisting Apparatus, of which the following is a specification.

This invention relates to ammunition hoisting apparatus of the kind in which the projectile and powder charges are raised in a hoist cage to a working chamber where they are transferred to an upper or gun loading cage which carries the projectile and powder charges to the breech of the gun.

20 According to this invention we provide in addition to the said gun loading cage, an auxiliary projectile cage or hoist, the chief purposes of which are to enable the guns to be supplied with projectiles from the working chamber in the event of the gun loading cage becoming inoperative and also to replenish the projectile bins in the space inclosed by the shield. The cage is preferably provided with a pivoted tray which is capable of being moved about its pivot by hand, so that it can be caused to assume an approximately vertical position prior to the ascent and descent of the cage, and an approximately horizontal position when it is desired to load the tray in the working chamber and to remove the projectile when the tray is above the shield floor.

In order that the said invention may be clearly understood and readily carried into effect we will describe the same more fully with reference to the accompanying drawings, in which:

Figures 1 and 2 are respectively a side elevation and an end elevation showing in
45 a more or less diagrammatic manner a constructional form of our improvements, and

Fig. 3 is an enlarged view of the auxiliary projectile cage.

A is the shield and A' the working chamber, B represents the auxiliary projectile cage and B', B' are its guide rails. B² is the projectile tray which is pivoted to the cage at b^x. C is the press for raising the said

auxiliary cage. It will be observed that in Figs. 1 and 2 the said cage is shown in two 55 different positions which as a matter of fact are never occupied by the cage at any one time.

In the example shown the hoist rope C is attached at c (Fig. 2) to the underside of the 60 shield floor at one side of the guide rails B' B' and after passing over sheaves b' b' carried by the lower part of the cage B is led by another sheave b² arranged at the other side of the guide rails to the ram of the 65 press C; in this manner a clear space is obtained to enable the tray B² to be swung to and from its horizontal position when in the working chamber without any danger of fouling the hoist rope, and the latter is conveniently arranged wholly below the shield floor. It will be obvious that an electrically or otherwise driven winch may be used instead of the press C for hoisting the cage.

A locking device is employed for retaining 75 the tray B² in either its vertical or its horizontal position, this device preferably comprising, as shown in Fig. 3, a spring catch or bolt b³ carried by the tray and adapted to engage with one or other of two notches 80 b⁴, b⁵ formed in a quadrant B³ on the cage B; this spring catch is capable of being disengaged from the notches by a pivoted handle B⁴. The guide rails B', B' for the cage are preferably disposed between the girders 85 at the rear of the turntable and may be straight but inclined slightly to the vertical. The shield floor is formed with a hole to enable the cage to pass to the upper side of the floor and this hole may be closed by a 90 door or shutter when the cage is not in use.

The projectiles may be placed in position on the tray by a grab A² or the like carried by a rail A³ in the working chamber A' and a similar device a² may be employed within 95 the space inclosed by the shield for removing the projectiles.

The cage may as shown have a transverse tie bar B³ at its upper end, and in this event after a projectile has been placed on the tray 100 B² in the position shown by chain lines in Fig. 3, it must be pushed backward until its base bears against the end of the tray prior to its being tilted into the vertical position. Similarly prior to the removal of the projectile it must be moved forward in the tray 105

so that it will clear the tie bar when the projectile is raised by the grab a^2 .

What we claim and desire to secure by Letters Patent of the United States is:—

- 5 1. In ammunition hoisting apparatus, the combination with the gun loading cage, of an auxiliary projectile cage additional to the usual gun loading cage, for raising projectiles independently of said gun loading cage, a transversely pivoted tray forming part of said auxiliary cage normally occupying a horizontal position and being capable of being moved to an approximately vertical position for the ascent and descent of the 10 cage, and single means for locking said tray to the auxiliary cage in either of its said 15 positions.
2. The combination with a gun shield and a gun loading cage, of an auxiliary projectile cage, additional to the usual gun loading cage, for raising projectiles independently of said gun loading cage, a transversely pivoted tray forming part of said auxiliary cage, said tray being moved into an approximately vertical position for the ascent of the 20 cage, a hoisting motor for said auxiliary cage, a rope connecting said motor to the auxiliary cage, said rope being arranged to leave a clear space behind said auxiliary 25 cage.

Copies of this patent may be obtained for five cents each, by addressing the "Commissioner of Patents, Washington, D. C."

cage to enable its tray to be rocked to and from its horizontal position.

3. In ammunition hoisting apparatus for gun turrets, the combination with the gun loading cage, of an auxiliary projectile cage, additional to the usual gun loading cage for raising projectiles independently of said gun loading cage, a transversely pivoted tray forming part of said auxiliary cage, said tray being moved into an approximately vertical position for the ascent of the 35 cage, guide rails for said auxiliary cage, a hoisting motor for said auxiliary cage, said motor being arranged at one side of the guide rails, a rope connected at one end to the motor and at the other end to a part of 40 the shield or turret floor on the opposite side of the guide rails to that at which the motor is disposed and sheaves carried by said auxiliary cage, these sheaves being so arranged that the rope leaves a clear space 45 behind said auxiliary cage to enable its tray to be rocked to and from its horizontal position.

In testimony whereof we affix our signatures.

ARTHUR TREVOR DAWSON.
JAMES HORNE.
